UNITED STATES PATENT OFFICE.

HENRY HARTZELL WAUGH, OF BROOKLYN, NEW YORK.

BOTTLE-HEATER.

No. 820,029.

Specification of Letters Patent.

Patented May 8, 1906.

Application filed March 21, 1905. Serial No. 261,218.

To all whom it may concern:

Be it known that I, HENRY HARTZELL WAUGH, a citizen of the United States, residing at Brooklyn, in the county of Kings and State of New York, have invented a new and useful Bottle-Heater Specially Designed for the Rapid Heating of Nursing-Bottles, of which the following is a specification.

This invention relates to a bottle-heater of the nature of a water-bath, and has for its object to provide a heater so constructed that a quantity of water will fill the heater and cover the body of the bottle and during the heating will cause a vertical or shaking motion to be imparted to the bottle and its contents, such a construction enabling the water in the heater to be heated in a very short time.

To this end the present invention consists in the construction, combination, and arrangement of parts set forth in and falling within the scope of the appended claims.

In the drawing the figure shows a vertical cross-sectional view of my device having a bottle therein, such bottle being shown in elevation.

Referring now to the accompanying drawing in detail, the letter A indicates a tubular member, preferably cylindrical in form, which is made slightly larger in cross diameter than the bottle to be heated, and near its upper end such a member is formed with an inwardly-extending bead or rib C, designed to prevent the bottle from contacting with and lying flat against the side of the cylindrical member. Near the lower end of the tubular or cylindrical member I provide a bead or rib E, which is preferably slightly larger than the rib or bead C. This rib E is designed for the same purpose as the rib C—that is, to prevent the bottle lying flat against the side of the cylinder; but in addition to this function it assists in causing the vertical motion to be imparted to the bottle by reason of the fact that when the steam rapidly generated in the base and partially confined by the groove forces the bottle up slightly the space between the groove and the bottle will be increased, allowing the easy passage of the slightly-compressed steam and a free flow of water into the base. Especially is this when the bottle is constructed, as shown in the present drawing, with the lower portion of its body slightly tapered or inclined inwardly toward the base. The vertical shaking motion which is imparted to the bottle will agi-

tate the contents of the latter, and thus cause a more rapid heating of the same.

The base F, which is connected to the tubular member A, is preferably made broad, 6c hollow, and comparatively shallow, and the lower plate thereof, to which the heat is applied, is slightly spaced apart from the upper portion thereof and is provided with corrugations or depressions H, designed to decrease 65 the water contents entering between the upper and lower plates of the base, such corrugations also preventing the accidental forcing of the upper plate flat against the lower one, and in addition increases the heating- 70 surface and prevents the bottom of the bottle from contacting with the lowest part of the lower plate, inasmuch as such bottle will rest upon one of the inwardly-projecting or raised surfaces of the corrugated part. 75

The handle of the device is shown at D, while the water-chamber formed at the base is designated by the letter N. In the present instance I have shown a bottle B of a certain construction; but it will of course be understood that there may be modification and variation in construction of my device, so as to enable it to receive any character of bottle. 8c

Having thus described my invention, what I claim, and desire to secure by Letters Patent, is—

1. A bottle-heater having a relatively wide base member composed of plate-like members spaced apart to form a water-chamber, and provided with a corrugated portion, and a 90 relatively narrow tubular member connected to said base, and communicating therewith.

2. A bottle-heater having a relatively wide base member formed with a water-chamber, a tubular member connected to and in communication with said base and adapted to receive a bottle, and means on the interior of the tubular member for preventing the bottle from contacting or lying flat against the side walls of the tubular member, and to partially confine steam passing between the sides of the bottle and the sides of the tubular member. 95 100

3. A bottle-heater having a relatively wide base portion provided with a corrugated surface on which the base of the bottle is adapted to rest, a relatively narrow tubular member carried by the base and in communication therewith and adapted to receive a bottle, and means for partially confining or obstructing the passage of steam between the bottle and the sides of the tubular member. 110

4. A bottle-heater having a relatively wide base formed of plate-like members spaced apart, the lowermost of said members having projecting surfaces extending inwardly therefrom, and a relatively narrow tubular member connected to the uppermost plate, and communicating with said base.

5. A bottle-heater having a base formed of plate-like members spaced apart, the lowermost of said members having projecting surfaces extending inwardly therefrom, a tubular member connected to the uppermost plate and communicating with the base, and means projecting inwardly from the tubular member to prevent a bottle or the like lying flat against the sides of the tubular member.

6. A bottle-heater having a base portion formed of a plurality of plates designed to form a water-chamber, one of said plates having an indented surface, a tubular bottle-

containing member connected to the base and communicating therewith and ribs or beads extending inward from the wall of the tubular member designed to partially confine steam passing through the space between the 25 bottle and the tubular member.

7. A bottle-heater having a base formed of plate-like members spaced apart to form a water-chamber, a relatively narrow tube extending upward from said base and communicating therewith, and a rib or bead extending inward from the tubular member.

In testimony whereof I have signed my name to this specification in the presence of two subscribing witnesses.

HENRY HARTZELL WAUGH.
